CLAIM

The ornamental design for a food and beverage maker, as shown and described.

DESCRIPTION

FIG. 1 is a front elevational view of a food and beverage maker showing my new design;

FIG. 2 is a right side elevational view thereof, the left side elevational view thereof being a mirror image;

FIG. 3 is a rear elevational view thereof;

FIG. 4 is a top plan view thereof, the bottom plan view thereof being an inversion.

FIG. 1

FIG. 2

FIG. 3

FIG. 4
